UNITED STATES PATENT OFFICE

2,513,566

DISHWASHER

Frederick W. Kent, Milwaukee, Wis.

Application August 10, 1945, Serial No. 609,971

1 Claim. (Cl. 299—84)

1

My invention relates to a dish washer of the kind which can be installed on an ordinary kitchen faucet.

My improved dish washer includes a container for bar soap and a valve for controlling flow of water in such manner that in one position of the valve, water will be directed against and around the soap and the suds conveyed from thence to a nozzle from which the soapy water can be directed in needle-like streams to the dishes to be washed.

In another position of the valve, the soap is bypassed and hot rinse water can be passed through the valve to the nozzle for rinsing the dishes.

In another position of the valve, the soap chamber may be drained.

I also show a modified form of structure for directing the water against the soap.

With these and other objects in view, my invention consists in the construction, arrangement and combination of the various parts of my device whereby the objects contemplated are attained, as hereinafter more fully set forth, pointed out in the claim and illustrated in the accompanying drawings, wherein:

Figure 1 is a front elevation of the dish washer embodying my invention mounted on a faucet.

Figure 2 is a side elevation of the same, parts being shown in section, taken on the line 2—2 of Figure 1.

Figure 3 is a top or plan view, parts being broken away and parts being shown in section, and parts being shown in dotted lines.

Figure 4 is a vertical sectional view through the valve.

Figure 5 is a vertical sectional view through the valve and the soap-holding container.

Figures 6, 7, 8 and 9 are plan views of the valve in different positions.

Figure 10 is a vertical sectional view of the valve shown in Figure 6, taken on the line 10—10 of Figure 6.

Figure 11 is a vertical sectional view of the valve taken on the line 11—11 of Figure 7.

Figure 12 is a vertical sectional view of the valve taken on the line 12—12 of Figure 8.

Figure 13 is a vertical sectional view of the valve taken on the line 13—13 of Figure 9.

Figure 14 is a vertical sectional view taken on the line 14—14 of Figure 3, illustrating the nozzle.

Figure 15 is a front elevation of the disk in the nozzle, part of the nozzle being shown in section, taken on the line 15—15 of Figure 14.

Figure 16 is a vertical sectional view of a slightly modified form of my dish washer illustrating

2

another way of directing the water to the soap. Figure 17 is an enlarged vertical section of the nozzle for directing water against the soap, in the form of the device shown in Figure 16, taken on the line 17—17 of Figure 16.

In the drawings herewith I have used the reference numeral 10 to indicate an ordinary swinging faucet of the kind commonly found in kitchens and in connection with which my dish washer may be used.

The dish washer includes a soap container, indicated as a whole at 12 in Figure 1, and comprised of upper and lower members 15 and 14 screwed together at 16 as shown in Figure 2. A suitable gasket 18 is provided to prevent leakage from the container 12. The lower part 14 of the container has an annular horizontal shoulder 20 at its bottom, as shown in Figures 2 and 5. Inwardly from the shoulder is a circular depression 22, with a concave bottom. A substantially round plate 24 is supported on the bottom portion 22 and spaced above it by studs 26.

The top member 15 of the container 12 has an annular flange 28, Figures 2 and 5, spaced from the wall of the lower member 14 and terminating a very short distance above the annular shoulder 20.

A bar of soap 30 may be placed on the plate 24. Secured to the underside of the member 14 by bolts 32 is a tightly-seated sleeve 36 having a bore in which a valve casing 35 is rotatably mounted. Within the said casing there is a tapered valve 37 having the stem 38 on which is the controlling handle 39.

In the form of my invention now being described, the valve is planned to have four positions, to-wit, an "off" position, a "sudsing" position, a "rinsing" position and a "drain" position.

The water supply pipe to the valve is indicated at 40. It communicates with a passage 42 through the valve casing 35 and sleeve 36, leading to the valve 37. The valve 37 has a transverse passage 44, Figure 5, leading through it. There is a passage 46 through the wall of the sleeve 36 and through the wall of the casing 35, directly opposite the passage 42. In one position of the valve, the passage 44 registers with the passages 42 and 46. The passage 46 communicates with a passage 48 in the lower container member 14 which opens into the annular passage 50 formed around the flange 28.

The valve casing 35 and sleeve 36 have a passage 52 which registers with a passage 54 at the opposite sides of the sleeve 36 and casing 35 and with a passage 55 in the container member 14,

leading from the bottom portion 22. In the valve 31 is a cross passage 56 parallel with the passage 44 and which registers with the passages 52 and 54.

A pipe 58 is secured to the valve casing and is connected with a flexible hose 60, which has on its free end a nozzle 62 which will be later and more fully described.

When the parts are in the position shown in Figure 2, water enters through the pipe 40, passes through the valve to the annular passage 50, flows under the flange 28, and is discharged in a thin, annular sheet around and against the soap 30. The soapy water flows over the plate 24 and out through the valve to the nozzle 62, from which this soapy water may be discharged on to the dishes.

The valve is then in what may be called the "sudsing" position illustrated in Figures 2, 7 and 11.

The valve may also be adjusted to "rinsing" position. For this purpose there is provided in the surface of the valve 31, 90 degrees around the valve from the passage 44, a longitudinally-arranged groove 66 which, in the "rinsing" position of the valve, communicates with the passages 42 and 52. When the valve is in this position, water will flow from the faucet to the pipe 40 and to the valve and through the passage 66 in the valve to the pipe 58 and the nozzle 62. The valve is shown in Figures 4, 8 and 12 in this "rinsing" position.

Projecting upwardly from the bottom of the lower part 14 of the soap container 12, near the side wall thereof, is a pipe 68 which projects to a point close to the top of the member 15. The lower end of the pipe 68 communicates with a passage 70 through the bottom of the member 14. Passage 70 in turn communicates with a passage 72 through valve casing 35 and sleeve 36. The valve 31 has in its surface a slot 74 communicating with the passage 44 and adapted in one position of the valve, to communicate with the passages 72 and 70.

It will be seen that if the valve is in the position shown in Figure 2, the "sudsing" operation can be performed but the passage 74 will be inoperative. On the other hand, if the valve is turned 180 degrees from the position shown in Figure 2 to the position shown in Figure 5, some water will pass through the passage 48 in the manner hereinbefore described and some water will pass through the passages 74, 72 and 70 to the pipe 68 and discharge at the upper part of the soap container. Sudsing can be done while the valve is in this last-named position and some soap will be taken off by the water passing through the pipe 68. This will wash off the upper part of the soap and by closing the faucet valve and discontinuing the water from the faucet, the apparatus can then be permitted to drain.

Soap container supporting means

I provide soap container supporting means in the form of a rod 76 extending downwardly from the bottom of the valve casing 35 and terminating in a foot 78 designed to rest on the faucet 10.

The means for connecting the apparatus with the faucet for water flow also contributes to holding the apparatus on the faucet.

At the lower end of the pipe 40 is an elbow 80 from which projects a pipe 82 communicating with a faucet connector 84 in the form of a box-like member, with a central upwardly extending tubular member 86, which projects into the faucet.

cet. On the member 84 is a gasket 88. A collar 90 is secured to the faucet near its discharge end by set screws 92 or the like. Pivoted to the faucet connector 84 are links 93 which are in turn pivoted as at 94 to the arms of a locking yoke 96 having cam-shaped ends 98 adapted to engage the top of the collar 90, locking the faucet connector 84 in place.

By swinging the yoke 96 downwardly, the faucet connector can be disconnected and the entire apparatus can be lifted off the faucet.

The discharge pipe 58 is connected by an elbow 100 with a short horizontal pipe 102, Figure 2, and in turn to a flexible tube 60 already referred to. At the outer end of the flexible tube 60 are the parts forming the discharge nozzle. Tube 60 connects with a short pipe 61, which may function also as a handle.

An internally threaded collar 104 mounted on the pipe 61 is formed with an external annular shoulder 106, see Figure 14, and a projecting threaded portion 108. Screwed onto the threaded portion 108 is a larger diameter tube 110. The tube 110 may be molded plastic or any material suitable for the purpose. I preferably use plastic for the tube 110 and provide on the inside of the tube a plurality of projecting ribs 112 which terminate short of the threaded end of the tube 110. Between the ends of the ribs 112 and the collar 104 and tube 61, is loosely received a disk 114 having a plurality of holes 116 to admit the passage of fine streams of water. When the disk 114 is thus loosely mounted, the water from the tube 61 passes through the holes 116 and water can flow around the periphery of the disk 114. A considerable flexibility in operation is afforded by reason of the fact that the collar 104 is adjustable on the pipe 61. For example, by screwing the collar 104 a little farther on to the pipe 61, the tube 110 can be pulled toward the pipe 61 until the disk 114 is snugly gripped between the shoulders 112 and the pipe 61. In that position of the parts water cannot flow around the periphery of the disk 114 but must flow only through the perforations 116. I can get regulation of the operation of the nozzle by adjusting the tube 110 on the collar 104 on the pipe 61.

Operation

I shall now briefly review the operation of my dish washer.

Assuming that the soap 30 has been placed in position and the dish washer installed on the faucet and the faucet valve has been opened. Then if the handle 39 is in position to hold the valve as shown in Figure 6, nothing happens. This is the neutral position of the valve.

By turning the valve 90 degrees, water will be permitted to flow from the faucet to the pipe 40 and through the valve and passage 48 to the annular passage 50 formed around the flange 28, and thence in a thin annular sheet into the soap container and against the soap. Soapy water flows around the edge of the plate 24 to the outlet opening 55, Figure 2.

If the valve is in the position shown in Figure 2, no water flows through the pipe 68 because the passage 74 is closed. If the valve is turned to the position shown in Figure 5, some water will flow through the pipe 68. There is thus afforded an additional flexibility of operation. Water flowing through the passage 55 passes through the valve to the nozzle 62 and can be used for washing dishes. When it is desired to rinse the dishes with clear, hot water, the valve

is turned to the position illustrated in Figures 4, 8 and 12. Thereupon the rinse water flows through the passage 66.

In Figures 16 and 17 I have shown a slightly modified form of my device. In this form of the device a plug 120 is placed in the lower end of the passage 48, rendering that passage inoperative. I connect an elbow 122 and horizontal pipe 124 with the upper end of the pipe 68, and put a spray nozzle 126 on the inner end of the pipe 124 for discharging fine streams of water against the soap 30, for the sudsing operation. Otherwise the operation is as heretofore described with the exception that no water passes through the passage 48.

The spray head 126 is shown in Figure 17 in detail and comprises a box-like member, having on its under face a perforated concavo-convex disk 128.

While changes may be made in the details of construction and in the arrangement of parts, I desire to cover such modifications as may be included within the scope of my invention or the scope of the appended claim.

I claim as my invention:

In a dish washer for use with a faucet having a downturned outlet, said dish washer having a

soap chamber adapted to be disposed over the faucet, the combination comprising, a rigid tube for supplying water to the chamber, said tube having a horizontal leg for communication with and secured to the outlet of the faucet, a rigid leg spaced from said rigid tube and secured to the chamber and engageable with the upper surface of the faucet, and means for clamping the leg of said tube to the faucet.

FREDERICK W. KENT.
